(57) CLAIM

The ornamental design for an insole, as shown and described.

DESCRIPTION

FIG. 1 is a top, front, right side perspective view of an insole for the left shoe showing our new design;

FIG. 2 is a bottom, front, right side perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

The broken lines are not part of the claimed design.

The right shoe insole is a mirror image of the views of the left shoe insole.
